CLAIM

The ornamental design for a guide line clamp, as shown and described.

DESCRIPTION

FIG. 1 is a front, bottom, right side perspective view of a first embodiment of a guide line clamp showing my new design; FIG. 2 is a right side elevation view thereof; the left side elevation view being a mirror image;

FIG. 3 is a front elevation view thereof;

FIG. 4 is a rear elevation view thereof;

FIG. 5 is a top plan view thereof; and

FIG. 6 is a bottom plan view thereof; and

FIG. 7 is a front, bottom, right side perspective view of a second embodiment of my guide line clamp;

FIG. 8 is a right side elevation view thereof; the left side elevation view being a mirror image;

FIG. 9 is a front elevation view thereof;

FIG. 10 is a rear elevation view thereof;

FIG. 11 is a top plan view thereof; and,

FIG. 12 is a bottom plan view thereof.
